TRANSPORTABLE TANK

Herbert F. Dalglish, St. Paul, Minn., assignor to
Duaload Transportation Corporation, St. Paul,
Minn., a corporation of Minnesota

Application January 25, 1952, Serial No. 18,242

Term of patent 14 years

(Cl. D14—3)

To all whom it may concern:

Be it known that I, Herbert F. Dalglish, a citizen of the United States of America, residing at 284 Cherokee Avenue, St. Paul, county of Ramsey, State of Minnesota, have invented a new, original, and ornamental Design for Transportable Tank, of which the following is a specification, reference being made to the accompanying drawing, forming a part thereof, and in which:

Fig. 1 is a plan view of the transportable tank, showing my new design;

Fig. 2 is a side elevational view thereof;

Fig. 3 is an end elevational view of the transportable tank taken from the left side of Fig. 1; and

Fig. 4 is an end elevational view of the transportable tank taken from the right side of Fig. 1.

Fig. 5 is a perspective view of the transportable

tank taken from an elevated position at the left side of the transportable tank and from the left side of Fig. 1.

I claim:

The ornamental design for a transportable tank, substantially as shown.
